[57] CLAIM

The ornamental design for a body lotion applicator with pump-handle lotion reservoir and sponge-covered roller head, as shown and described.

DESCRIPTION

FIG. 1 is a front elevational view of the body lotion applicator with pump-handle lotion reservoir and sponge-covered roller head showing our new design;

FIG. 2 is a rear elevational view thereof;

FIG. 3 is a right view thereof;

FIG. 4 is a left view thereof;

FIG. 5 is a top plan view thereof; and

FIG. 6 is a bottom plan view thereof.

The portions of the underside of the notched surface above the roller that cannot be seen are not being claimed.

The undisclosed surfaces of the upper flanges and lower end of the handle shaft are planar and unornamented.
